COMPRESSING DEVICE FOR COLLAPSIBLE PASTE TUBES

Daniel S. Speese, Detroit, Mich.

Application June 25, 1957, Serial No. 667,922

5 Claims. (Cl. 222—102)

This invention relates to devices for compressing collapsible paste tubes to expel their contents.

An object of the invention is to provide a highly efficient device of such nature, designed for economical manufacture.

Another object is to provide in such a device a driving and a driven roller between which a paste tube is progressively compressed, and supporting means to journal said rollers.

Another object is to mount the driving roller on a fixed axis, and to mount the driven roller for lateral movement to and from the first, alternatively affording a tube-compressing position or a tube-releasing position.

A further object is to provide means for rotative actuation of the driving roller and to provide a ratchet wheel and pawl effective in the tube-compressing position of the rollers to limit rotation to a tube-compressing direction.

Another object is to provide spring means to urge the driven roller toward the tube-compressing position.

Still another object is to provide cam means to counteract said spring means and establish the driven roller in its tube-releasing position.

A further object is to provide a deflector to engage the progressively compressed portion of the paste tube and direct it to avoid the rollers.

These and various other objects are attained in the construction hereinafter described and illustrated in the accompanying drawings, wherein:

Fig. 1 is a side elevational view of the device.

Fig. 2 is a bottom plan view taken on the line 2—2 of Fig. 1 and rotated ninety degrees clockwise relative to Fig. 1.

Fig. 3 is a longitudinal section taken on the line 4—4 of Fig. 2 and rotated ninety degrees counter-clockwise thereto.

Fig. 4 is a longitudinal section taken on the line 4—4 of Fig. 2 and rotated ninety degrees clockwise thereto, showing the mechanism in its tube-compressing position.

Fig. 5 is a view similar to Fig. 4, showing the mechanism in its tube-releasing position.

Fig. 6 is a horizontal section taken on the line 6—6 of Fig. 4, and rotated ninety degrees counter-clockwise thereto.

Fig. 7 is a partial horizontal sectional view taken on the line 7—7 of Fig. 4 and rotated ninety degrees counter-clockwise thereto.

Fig. 8 is a partial vertical view taken on the line 8—8 of Fig. 5.

In these views, the reference character 1 designates a housing having side walls 2, a top wall 3, and a rear wall 4. The rear wall is preferably formed with a notch 4a to engage a conventional bracket 5 fixed as by screws 6 to a wall 7. Screws 8 may be used in addition to, or as an alternative to such bracket.

Between the lower forward extent of said side walls, a driving roller 9 having reduced end portions 9a, 9b is revolvable on a fixed axis. The end portion 9a journals in a bearing 10, which projects through a side wall and

2

mounts a collar 11 secured by a set screw 11a. The other end portion 9b journals in and projects through a bearing 12 set into the opposite side wall, and terminally carries an actuating knob 13.

5 A pair of bell cranks 14 are mounted on aligned pivot elements 15 which extend through annular spacers 16 and are respectively fixed in the side walls 2. Downwardly extending work arms 14b of said bell cranks receive between them a driven roller 17. The end portions of 10 the roller 17 are reduced in diameter and journaled in the work arms 14b on an axis parallel to that of the driving roller 9.

A pair of springs 18 mounted on pins 19 react between 15 fixed pins 20 and pins 21 projecting from the work arms 14b, strongly urging the latter about their pivotal axis to bring the roller 17 into a tube-compressing proximity to the roller 9. In such position a requisite slight spacing of the rollers is effected by collars 22 carried by the driving roller 9 on its aforesaid end portions 9a, 9b, and 20 of slightly greater diameter than such roller. Such collars peripherally abut the end portions 14a of the work arms 14b of said bell crank, which end portions are preferably arcuately formed to a radius slightly exceeding that of the driven roller 17. The slight spacing thus 25 achieved prevents the peripheries of the rollers from an otherwise severe collision when the springs 18 are permitted to snap the driven roller 17 into the tube-compressing position.

The sealed end of an ordinary paste tube A (Fig. 3) 30 is progressively upwardly drawn between and compressed by the rollers 9 and 17 to expel its contents, as desired, by rotation of the roller 9 by its knob 13. When the rollers are in their tube-compressing position, such rotation is permitted in one direction only. To prevent reverse rotation and consequent unintentional ejection of a 35 paste tube, a ratchet wheel 23, coaxially affixed to a collar 24 by rivets 25, is mounted on the roller 9, being removably secured on the end portion 9b thereof by a set screw 26 in said collar.

40 A third bell crank having its work arm formed with a pawl 27 is pivotally positioned by a pin 28 for engagement with and disengagement from the ratchet wheel. The rearwardly extending power arm 29 of said third bell crank is provided with a pin 30. A spring 31 mounted 45 on a pin 32, reacts between the pin 30 and the surface of a cam 35a to urge the pawl into engagement with said ratchet wheel.

50 Rearwardly elongated from the pivots 15, power arms 14c of the bell cranks 14 overhang a rock shaft 33 parallel to the rollers and terminally journaled in the side walls 2. Near the rock shaft ends, adjacent to the side walls, are hubs 34 and 35 secured by set screws 36. Such hubs are formed with similar arcuate cams 34a, 35a to actuate the arms 14c. A lever 37 extends downwardly 55 from the cam 34a for rocking the shaft between limiting positions established by stop pins 37a. As clearly seen in Figs. 3 and 7, when the lever is at the rearward limit of its travel the cams 34a, 35a are disengaged from the power arms 14c. Thus, the springs 18 are free to urge the bell cranks 14 about their pivotal axis bringing the driven roller 17 toward the driving roller 9 to their tube-compressing position. Moving the lever to its forward 60 limit of travel rocks the shaft 33, and, of course, the aforesaid cams to engage the latter with the power arms 14c, causing a rearward movement of the work arms 14b about said pivotal axis, and drawing said driven roller 17 away from the roller 9, to the tube-releasing position (Fig. 5).

The hub 35 bears an additional cam 35b to engage the 65 rearwardly extending power arm 29 of the pawl 27. When the lever 37 is at its rearward position the pawl remains engaged with the ratchet wheel 23. But when

the lever is moved to its forward position, as the cam 35a acts on the corresponding power arm 14c, the cam 35b acts on said power arm 29 to disengage the pawl from the ratchet wheel (Fig. 5). Such disengagement allows reverse rotation of the roller 9 by the knob 13 to facilitate, if necessary, the removal of an emptied paste tube.

It will be apparent, that as a paste tube is progressively drawn between the rollers, the length of the collapsed portion of such tube will increase. To avoid entanglement of said compressed portion with the bell cranks 14 and the rollers 9 and 17, it is preferred to secure to the top wall of the housing a deflector 38 of sheet material bent to extend toward and terminate in proximity to the roller 9. It has been found that the compressed portion of the paste tube, encountering the deflector 38, is directed arcuately over the roller 17 and downwardly from the housing.

In use, the device may be attached as previously described to any convenient surface. With the lever 37 at its forward limit, the sealed end of a paste tube may be readily inserted between the parted rollers 9 and 17. The lever 37 is then moved to its rearward limiting position, and the springs 18 force the roller 17 toward the roller 9, whereby the tube is strongly gripped between them. As the contents of such tube are required, the cap thereof is removed and the roller 9 is rotated by its knob 13, drawing the tube upwardly between said rollers to force out its contents. When the tube is empty, the lever 37 is moved to its forward limiting position, parting the rollers as described, for removal of such tube and insertion of a full one.

The pressure applied to the two rollers by the springs 18, is sufficient that the tube is thoroughly emptied. The rollers are preferably knurled or serrated to increase their grip on the tube.

What I claim is:

1. A paste tube compressing device comprising a supporting member including side walls, a driving roller journaled between said side walls on a fixed axis, a pair of arms, a driven roller journaled between said arms, pivot elements mounting the respective arms upon and between the respective side walls to afford movement of said driven roller, about the axis of said elements, to and from the driving roller between alternative tube-compressing and tube-releasing positions, means to rotatively actuate said driving roller whereby a paste tube may be progressively drawn between and compressed by said rollers, and its contents progressively expelled when said driven roller is in its tube compressing position, a spring urging the driven roller to said tube-compressing position, a ratchet wheel rigidly coaxially carried by the driving roller, a pawl, a pivot element mounting said pawl on a side wall, a spring urging said pawl about its pivotal axis to engage the ratchet wheel and prevent reverse rotation of the driving roller, a rock shaft journaled between the side walls, a cam rigidly mounted on the rock shaft and effective on one of said arms to move the driven roller to its tube-releasing position, a second cam rigidly mounted on the rock shaft and effective to disengage the pawl from the ratchet wheel to afford reverse rotation of said driving roller for removal of an empty paste tube, and means to rotatively actuate said rock shaft, said cams taking substantially concurrent effect responsive to such rotative actuation.

2. A paste tube compressing device comprising a supporting member including side walls, a driving roller journaled between said side walls on a fixed axis, a pair of bell cranks, having power arms and work arms, a driven roller journaled between said work arms, aligned

pivot elements mounting the respective bell cranks upon and between the respective side walls to afford movement of the roller, about the axis of said elements, to and from the driving roller between alternative tube-releasing and tube-compressing positions, means to rotatively actuate the driving roller whereby a paste tube may be progressively drawn between and compressed by said rollers and its contents progressively expelled when said driven roller is in its tube-compressing position, a spring acting on one of said work arms to urge said roller to said tube-compressing position, a ratchet wheel rigidly coaxially carried by the driving roller, a pawl, a pivot element mounting said pawl on a side wall, a spring urging said pawl about its pivotal axis to engage the ratchet wheel and prevent reverse rotation of the driving roller, a rock shaft journaled between said side walls, a cam effective on one of said power arms to move the roller to its tube-releasing position, a second cam effective to disengage said pawl from the ratchet wheel to afford reverse rotation of the driving roller for removal of an empty paste tube, and means to rotatively actuate said rock shaft, said cams taking substantially concurrent effect responsive to such actuation.

3. A paste tube compressing device as described in claim 2, said first and second cams being integrally formed upon a hub rigidly secured to the rock shaft.

4. A paste tube compressing device comprising a supporting member including side walls, a driving roller journaled between said side walls on a fixed axis, a pair of bell cranks, having power arms and work arms, a driven roller journaled between said work arms, aligned pivot elements mounting the respective bell cranks upon and between the respective side walls to afford movement of the roller, about the axis of said elements, to and from the driving roller between alternative tube-releasing and tube-compressing positions, means to rotatively actuate the driving roller whereby a paste tube may be progressively drawn between and compressed by said rollers and its contents progressively expelled when said driven roller is in its tube-compressing position, a spring acting on one of said work arms to urge said roller to said tube-compressing position, a ratchet wheel rigidly coaxially carried by the driving roller, a third bell crank having a power arm and a work arm, a pivot element mounting said bell crank on a side wall, said work arm being formed with a pawl, a spring urging said pawl about its pivotal axis to engage the ratchet wheel and prevent reverse rotation of the driving roller, a rock shaft journaled between said side walls, a cam effective on one of said power arms to move the roller to its tube-releasing position, a second cam carried by said rock shaft and effective upon said power arm to disengage said pawl from said ratchet wheel to afford reverse rotation of said driving roller for removal of an empty paste tube, and means to rotatively actuate said rock shaft, said cams taking substantially concurrent effect responsive to such actuation.

5. A paste tube compressing device as described in claim 4, said first and second cams being integrally formed upon a hub rigidly secured to the rock shaft.
